UNITED STATES PATENT OFFICE.

JOHN DARBY, OF SUMMIT, NEW JERSEY, AND HARRY C. JONES, OF LARCHMONT, NEW YORK, ASSIGNORS TO LITHOPRINTEX CORPORATION, OF NEW YORK, N. Y., A CORPORATION OF NEW YORK.

PHOTOMECHANICAL APPARATUS FOR TRANSFERRING DESIGNS FROM FLAT TO CYLINDRICAL SURFACES.

Application filed December 23, 1922. Serial No. 608,652.

The invention relates to photomechanical apparatus for transferring designs from flat to cylindrical surfaces and more particularly to apparatus for this purpose embodying 5 means for moving the design plate or transparency linearly simultaneously or in unison with the rotary movement of the cylindrical surface while the design is projected.

It has heretofore been proposed to transfer designs from a flat surface to a cylindrical surface both by contact printing and photomechanically, and the manner of preparing the sensitized cylindrical surface, the manner of treating same to etch or permanently record the transferred design on 15 the cylindrical surface, as well as the various uses to which such cylindrical surfaces thus completed may be put, are now well understood by those skilled in the art, and 20 need not be discussed herein.

For the sake of brevity in the following description the cylindrical surface will be referred to as the roller since a printing roller is a common embodiment of these 25 printing surfaces. But it will be understood that where in the specification and claims the terms "roller" and "complete revolution of the roller" are used, such expressions are to be understood as being broad enough to include, respectively, any cylindrical or curved sensitized surface and the peripheral movement thereof necessary to take the total height of the design to be transferred thereto. It will also be understood 30 that the term "design" is used as signifying any photographic plate or transparency bearing the design or any other suitable form of the design to be transferred.

One of the principal objects of the invention is to provide means in the connection 40 between the carrier for the design plate and the rotary support for the sensitized roller, which will cause the design to move linearly at a rate of speed that is constant 45 with respect to the peripheral velocity of the sensitized roller throughout the complete revolution of said sensitized roller so as to produce an accurate reproduction of 50 the design as transferred to the roller.

The invention in some aspects is intended as an improvement upon the apparatus

shown and described in United States Letters Patent No. 1,051,997, granted February 4, 1913.

The invention consists in the novel features, arrangements and construction and combinations of parts shown and herein-after described in accordance with the preferred embodiment thereof, and the invention will be more particularly pointed out in the appended claims.

Further objects and advantages of the invention will more fully appear from the following description taken in connection with the accompanying drawings illustrating, by way of example, the present preferred embodiment of the invention.

Referring to the drawings,—

Fig. 1 is a side elevation of a machine embodying the invention;

Fig. 2 is an enlarged elevation, partly, in section, of a part of the machine shown in Fig. 1;

Fig. 3 shows a detail taken on line 3—3 of Fig. 2 looking in the direction of the arrow;

Fig. 4 is a top plan view of the machine;

Fig. 5 is an enlarged elevation, partly in section, of the machine taken on line 5—5 of Fig. 1 looking in the direction of the arrow, and showing the front of the design carrier and related apparatus;

Fig. 6 is an enlarged view, partly in section, taken on line 6—6 of Fig. 5;

Fig. 7 is an enlarged detail of gearing shown in Fig. 4;

Fig. 8 is an enlarged view, partly in section, showing apparatus providing a light slot in front of the sensitized plate;

Fig. 9 is an enlarged elevation, partly in section, showing apparatus providing a light slot in front of the sensitized roller;

Fig. 10 is an enlarged elevation, partly in section, and with certain parts broken away, looking toward the sensitized roller as shown in Fig. 4;

Figs. 11 and 12 illustrate enlarged views of details hereinafter described;

Fig. 13 is a side elevation of a modification of the machine shown in Fig. 1; and

Fig. 14 is a diagrammatic illustration.

A brief general description of the arrangement and operation of the parts will first be

given and this will then be followed by a detailed description of the arrangement, construction and operation of the parts.

Referring more particularly to the drawings, Figs. 1, 4 and 5, 1 is the design carrier adapted to carry any suitable form of design, pattern or picture to be reproduced on the sensitized roller, such for example as the photographic plate or transparency 2, said carrier being adapted, through the operation of suitable apparatus hereinafter described, to move vertically upon parallel upright guides 3, the design plate 2 being secured in any suitable well known manner to the carrier 1, and the latter being adjustable vertically on the guides 3 to any suitable position from which it is to be moved downwardly in unison with the rotary movement of the sensitized roller.

20 The vertical guides in this embodiment of the invention are rigidly secured to the horizontal frame 4 of the machine. At the other end of the frame 4 there is provided a suitable rotary support for the sensitized roller 25 which in the present form of the machine is illustrated as a rotary member 5 to which the sensitized roller 6 is suitably coupled for rotation therewith as hereinafter described. This rotary member 5 is driven in any suitable manner from a power shaft 7 which is also operatively geared to move the plate carrier vertically on its guides. To the power shaft is geared suitable automatic stop apparatus comprising a gear wheel 8 having a laterally projecting pin 9 adapted, when released by lever 10 to permit the wheel to rotate through a half revolution whereupon the pin 9 will strike a stationary co-operating stop bracket 11 to arrest the rotation of the wheel, and with it the rotation of the rotary support 5. The gearing is such that the rotary support will make one complete revolution for a half revolution of the stop wheel 8. The connecting means between the rotary support 5 and the plate carrier 1 comprises what might generally be termed adjustable differential apparatus 12 which will cause the design carrier to be moved vertically the desired distance on its vertical guides for one revolution of the rotary support 5, and hence for one revolution of the sensitized roller 6.

Between the design carrier and the sensitized roller 6 there is mounted on the horizontal frame 4 a lens carrier 13 carrying a lens for projecting the design image onto the sensitized roller. In the present embodiment of the invention this lens carrier is slidably movable only over a somewhat limited distance along the horizontal frame for the purpose of getting proper adjustments of the focus of the lens, but without providing such a length of movement as to use different size lenses, and without providing for image projections in various ratios. As is

well understood, a suitable adjustable light source, shown somewhat diagrammatically at L, Figs. 1 and 4, will be provided behind the design plate with a suitable shield between it and the design plate so as to permit the light rays through a properly shaped opening, to emanate from the light source onto the design plate. It is understood that bellows or light shields 13' may also be used along the optical axis where desired.

70 Referring now more in detail to the roller end of the machine, we will describe, in connection with Figs. 1, 4, 10 and 11, means for rotating the roller and for adjusting the same with respect to the focal plane of the 80 lens.

75 The left-hand end of the machine is provided with upright pillow-blocks 14 and 15, the pillow-block 14 having a suitable bearing for the rotary support 5 to which is suitably secured worm wheel 16, and at the inner end of the rotary support 5 any suitable means, such as illustrated by a coupling sleeve and nut 17, is provided for coupling to the rotary support a mandrel 18 on which the roller 6 is mounted. The other end of the mandrel is journaled in any suitable manner in pillow-block 15, and the position of the roller longitudinally of the mandrel is adjusted in any suitable manner, such for example as by adjustment nuts 19, 19' threaded onto the mandrel and bearing against washers or sleeves 20.

85 The roller is rotated in any suitable manner, such for example as by the drive shaft 7 having a worm 21 meshing with the worm wheel 16, the shaft 7 being driven in any suitable manner as by a pulley 22.

90 It is necessary to adjust the sensitized roller somewhat back and forth along the carriage so that rollers of different size can be brought into position where their sensitized surface is tangent to the focal plane of the lens, and for this purpose the pillow-blocks 14 and 15, as shown in Figs. 4 and 10, are slidably mounted on guideways 23, 23' in the horizontal frame, each pillow-block being provided with a short rack 24 meshing with a gear 25, these gears being suitably keyed to a transverse shaft 26 journaled in the main frame and carrying a worm gear sector 27 keyed thereto and in turn meshing with a worm 28 operated by hand wheel 29.

95 It will be seen from this that as the hand wheel 29 is rotated in one direction or the other, it will cause the rack and pillow-blocks to move back and forth along the main frame so as to adjust the sensitized roller 7, to and from the focal plane of the lens, the location of which is indicated by the vertical surface 30 of the adjustment-determining means 31 (see Fig. 11). This back and forth movement of the pillow-block obviously requires a corresponding to and fro movement of the worm 21 along 100

shaft 7, and to accomplish this purpose any suitable known means may be provided. In the present instance the shaft 7 at its left-hand end is journaled in bearings 32, 32' carried by a journal bracket 33, suitably bolted as at 34 to the pillow-block to move therewith, the shaft 7 being adapted to freely slide in said bearing members while the worm 21 is slidably keyed on the shaft to permit relative movement of the shaft. The worm itself may be adjusted back and forth relative to the shaft between the two bearing members 32, 32' in any suitable and well known manner as by washers and nuts to take up lost motion or the like, the same not being illustrated as it is well understood by those skilled in the art. With this construction it will be seen that when the hand wheel 29 is rotated to move the roller back and forth on the main frame, the worm 21 and the bearing members 32, 32' will move as an integral part with the pillow-blocks.

In order that the sensitized roller may be allowed to make exactly one complete revolution and no more while the design is being projected thereon, so that if the movement of the design carrier with respect to the circumference of the roller is properly adjusted the design will exactly meet on the roller, it is necessary to provide accurate means for starting and stopping the roller. In the present embodiment of the invention stop apparatus is provided as heretofore mentioned, which will take care of this feature, the stop apparatus consisting of the stop wheel 8 mounted on a shaft 8' and geared to a worm 35 keyed to the power shaft 7. This worm is of such a pitch with respect to worm 21 on the same shaft, that as stated, a half revolution of the worm wheel 8 will allow exactly one revolution of the worm wheel 16, and hence of the sensitized roller 6. It is preferred to provide a rigid positively acting release and stop for this purpose, and to connect the power to the shaft by a suitable yielding connection such for example as a belt on the pulley 22 that may be allowed to slip after the stop pin 9 engages the stop bracket 11. Normally the control lever 10, which is swiveled on a pin 31, has its lower notched end engaging the stop pin 9, in which position the lever is held by a spring 37. With the belt running, as soon as the control lever 10 is thrown to the right, the wheel 8 being released, rotates for exactly one-half revolution whereupon it engages the bracket 11, which positively arrests further rotation of the wheel 8 and hence further rotation of the sensitized roller rigidly geared thereto, whereupon the power belt is allowed to slip until the power is shut off, or the application of power may be automatically terminated in any suitable manner. The stop bracket 11 is adjustably mounted in any suitable manner to give accurate adjustments for stopping purposes, and in the present instance the bracket 11 is swiveled on a pin 38 and is provided with a transverse slot 39 through which extends a clamping screw 40. With this arrangement, when the screw 40 is released, the bracket may be swung more or less about its pivot 38 to slightly adjust the height of the arresting flange of the bracket. Once this adjustment is accurately obtained, the bracket may be locked in this position.

This mechanism for operating the design carrier simultaneously with the roller will now be described.

Referring to Figs. 1, 4 and 7, it will be seen that the shaft 8' extends transversely of the main horizontal frame, being journaled in suitable brackets 41, 41', and that it is provided with spur gears 42, 42', one adjacent each side of the main frame in alignment with longitudinally slidable connecting rods 43, 43'. The lower side of each rod (see Fig. 7) is provided with a rack 44 meshing with the corresponding spur gear, so that as the shaft 8' is rotated, these spur gears 42, 42' will actuate the rods 43, 43' to slide them back and forth through suitable guide brackets 45, 45' and 46, 46'. At the other end of each of these rods there is connected the previously mentioned differential apparatus 12, 12', for translating a predetermined invariable horizontal movement of these rods, corresponding to one complete rotation of the sensitized surface, into a variable predetermined vertical movement of the design carrier, depending upon the adjustment of said differential apparatus.

We will next describe said differential apparatus and the manner in which it operates to move the carriage at a rate of travel that is constant with respect to the peripheral velocity of the sensitized roller during the projection of the design image onto the sensitized surface.

Referring to Figs. 1 to 6, inclusive, the horizontal rod 43, as best shown in Figs. 2 and 4, is rigidly connected at its right-hand end to a horizontally movable slide or carriage 47, the connection in the present instance being made by having the threaded extremity of the shaft pass through a bracket 48 and locked with respect thereto, by means of adjustable locking nuts 49. These nuts and the threaded portion of the shaft permit the slide 47 to be adjusted on the end of the rod 43 so as to adjust the slide with respect to the vertical guides 3, to the position from which it is to start its movements. This slide in the present instance comprises a longitudinal bar 50 having at its ends downwardly projecting portions or lugs 51, 51' in which are cut horizontal grooves 52 (see Fig. 3) adapted to slidably engage a guide or track bar 53 rigidly secured to the main frame in any suitable manner as by

brackets 54, so that as the rod 43 is moved forward by the rotation of the power shaft, the carriage 47 is caused to move from its predetermined starting point along the track 53 for a definite distance transverse to the vertical guides of the design frame.

An inclined guide bar or slide 55 is provided with a swivel pin 56 near the left-hand end of the horizontal carriage, the pin 10 being preferably threaded into the guide bar and extending from the surface thereof through a bearing boss 57 on the horizontal slide 47, and secured therein in any suitable manner, the center of the pin being preferably 15 in alignment with the longitudinal center line of the slide bar 55. As shown in Fig. 4, the slide bar 55 is somewhat spaced laterally from the horizontal bar 50 of the sliding carriage 47, for the purpose of permitting 20 the movement of a slide block, hereinafter mentioned, along the inclined slide 55.

The upper end of the inclined slide bar 55 is likewise provided with a pin 58 the center 25 of which also lies in the center line of the bar. This pin projects laterally from the face of the bar and extends through an arced slot 59 formed in an upright extension 60 of the horizontal carriage 47. The 30 pin is provided with either an enlargement or a sleeve 61 extending from the face of the bar 55 to the inner face of the slot, and the pin is adapted to have a sliding fit within this slot so that the bar 55 may be swung 35 about its pivot 56 through an arc equal to the length of this slot, for the purpose of adjusting the angularity of the bar with respect to the guide track 53, or in other words, with respect to the horizontal path 40 of movement of the carriage 47. The outer end of the pin 58 is threaded, and provided with a locking nut 62 having a suitable handle 63, so that by turning the nut the bar 55 is rigidly clamped in its adjusted 45 angular position, the slot member being at such time rigidly clamped between the outer face of the sleeve 61 and the inner face of the lock nut 62. When the bar 55 is thus 50 adjusted in its slot and clamped in position, it will be seen that the horizontally movable carriage 47 with its rigidly clamped bar 55, move together transversely of the uprights 3. In order to operatively connect 55 the design carriage with the slide bar 55, any suitable form of slide block may be provided operatively related to the bar 55 so as to engage and be moved by the same, the block itself being suitably connected to the design carriage so that as the straight uniformly inclined bar 55 is moved horizontally 60 past the guides for the design carriage, the block, by its engagement with the bar 55 will cause this carriage to move downwardly. For this purpose we provide a 65 slide block 64 comprising in this instance a

triangular plate 65 carrying at its angles rollers 66, 66', 66'', the spacing being such that the rollers just touch the opposite edges of the bar with a snug rolling or sliding fit and without lost motion. This slide 70 block should be swivelly connected with the design carriage so as to rock about its swivel axis to bring the opening through the rollers in proper alignment with the bar 55 for various adjusted positions of the bar 75 55, and for this purpose the triangular plate is provided with a pin 67 (Figs. 5 and 6) extending through bearings in a boss 68 formed on a vertical slide 69 which also operates on the vertical guides 3 on which 80 the design carriage moves, this vertical slide 69 being suitably connected with the design carriage so that the two are moved together when actuated by the slide block. The pin has nuts 67' securing it in place. For the 85 present purpose of considering the action of the slide block 64, it might be assumed that the slide 69 is a part of the design carriage.

It will be understood that the differential 90 mechanism described with respect to one side of the machine is duplicated on the other side of the machine so as to connect rod 43' to a vertical slide block 69' in the same manner as has been described for the 95 connection of rod 43 to the vertical slide 69.

It will be apparent from the foregoing description that with an inclination of the slide bar 55, as the horizontal carriage 47 carrying bar 55 is moved forward transverse to the vertical guides 3, the slide block 100 64 will be caused to move downwardly, thus moving the design carriage downwardly on its vertical guides, and it will be obvious that with a given throw or travel of the 105 horizontal carriage 47 the extent of the vertical movement of the block and design carriage will be proportional to the angle formed between the bar 55 and its horizontal path of movement; or between the bar 55 and the horizontal bar 50 to which it 110 is swiveled.

In the present mechanism illustrated, the extent of travel of the block 64 along the vertical downward projection of the center 115 of its swivel pin 67 corresponds to the tangent of the right-angle triangle of which the bar 50 is the base and the bar 55 the hypotenuse. It will be seen that with the mechanism described the rate of movement 120 of the block 64 and design carriage will be constant with respect to the rate of travel of the horizontal carriage 47 throughout the stroke or travel of the latter, and hence the rate of movement of the design carriage 125 will be constant with respect to the peripheral velocity of the sensitized roller throughout the complete rotation of the latter. This is a very important feature in order that the design on the transparency 130

may be accurately reproduced on the sensitized surface. If the rate of movement of the design carriage should vary with respect to the peripheral velocity of the roller at any portion of the revolution of the roller while the design is being projected thereon, the design as projected on the roller during such period of time will be distorted with respect to the portion projected at another period of time. That is to say, if through a half revolution of the roller the ratio of the rate of movement of the design to the peripheral velocity of the roller is 1 to 4, but during the last half of the revolution of the roller the ratio is .75 to 4, it will be apparent that during this last half of the revolution of the roller the portion of the design being transferred thereon from the relatively slowly moving design plate will be stretched out around the roller with respect to the other half, and will be correspondingly shortened on the roller in case the design carriage should be speeded up with respect to the peripheral velocity of the roller during the last half of the latter's rotation.

If in designing the machine we determine on a definite throw or travel of the horizontal carriage 47 for a complete revolution of the sensitized roller, or for a complete revolution of the gear 16; say a travel of ten inches, and in assembling the machine so adjustably connect the carriage 47 onto the end of the rod 46 that at its neutral or zero position shown in the drawing, the distance from the center of the pivot pin 56 of bar 55 to the downward vertical projection of the center of the pin 67 in the slide block 64, is equal to this throw of the carriage, then for each revolution of the sensitized roller the horizontal carriage 47 will be moved to an extent sufficient to bring pin 56 into alignment with the vertical path of travel of pin 67. It will then be a very simple matter to provide a scale reading in linear dimensions, with respect to which the angularity of the bar 55 may be adjusted to move the block 64 and the design carriage for any desired travel of the design carriage. This travel will normally be equal to the height of the design on the carriage.

This may be illustrated graphically in the simplest form by Fig. 14, wherein the line 55' represents the position of the inclined bar 55, and the horizontal line 50' represents the bar 50 to which the bar 55 is swiveled, as indicated by the point 56', while the point 67' represents the center of the pin 67, and the dotted line 67'' represents its vertical downward projection or path of movement when the block is moved by the shifting of the horizontal carriage. Along this dotted line 67'' we provide a scale 67^a graduated from the horizontal line 50' pref-

erably in the same linear units as it is desired to measure the height of the design in. It will be seen that in order to set the apparatus to move the design through a definite vertical distance equal, say, to the height of the design, it is only necessary to unclamp the swivel bar 55 and set it at an angle such that the line 55' intersects the vertical scale at the reading equal to the distance through which the carriage is to be moved. For example, if it is desired to move the carriage 8 inches, it will only be necessary to adjust bar 55 to such an angle that line 55' will intersect the scale at 8, whereupon the horizontal slide 47 is moved, the block 64 and design carriage will be moved through the said 8 inches and always at a uniform rate with respect to the peripheral velocity of the roller.

In the present apparatus it is not convenient to arrange the scale at this point, so that the scale has been transposed to the design carriage itself to be read with relation to the slide 69 to which the slide block 64 is connected, as will shortly be described.

In the present form of the machine it has been designed specially for a six-inch diameter sensitized roller, and the throw or travel of the horizontal carriage 47 is made about 18 $\frac{1}{6}$ inches in order to get mechanically desirable inclinations of the bar 55 within the limits for which the machine is intended. Also, the bottom of the slot 59 is carried to a point at which when occupied by the pin 58, the vertical travel of the design carriage will be say 5 inches, which is estimated to be the minimum movement for designs to be used in this particular machine, and hence the scale above referred to could commence at 5.

Referring now more particularly to Figs. 1, 4 and 5, it will be noted that the design carriage 1 is counterbalanced on its vertical guides 3, by counterweights 70, 70' connected to the carriage over wheels 71, 71' mounted on cross bar 72 connecting the up-

In order to produce an accurate and fine adjustment of the design carrier 1 on the vertical guides 3, 3, the following apparatus is provided. A hand wheel 73 is provided for rotating a horizontal shaft 74 journaled in brackets 74' mounted on the carrier, the shaft carrying at its ends bevel gears 75, 75' which operate upon corresponding bevel gears 76, 76' keyed to vertical screws 77, 77' which are provided at their upper ends with suitable thrust collars 78, 78' at each side of their bearings on the carrier, the lower ends of these screws engaging in threaded bosses 79, 79' forming a part of or suitably secured to the vertical slide 69, 69'. It will be seen from this that if when the clamp nut 63 on the pin 58 is tightened to clamp in a fixed position the slide bar 55 and

hence the vertical slide 69 connected thereto, the hand wheel 73 is rotated to rotate screws 77, 77', this will cause the design carriage to move vertically on the guides 3 with respect to the slide 69, 69'. This adjustment of the design carrier on its vertical guides 3 is for the purpose of setting the horizontal base line of the design, i. e., the lower end of the design at its zero position, which means at a position where it coincides with the center of light slot 80 (Fig. 5) hereinafter referred to. It might be here noted that the starting point of the scale 81 on the design carrier may also coincide with the center of this slot 80. It will also be observed that when the hand wheel 73 is not being operated to produce relative movement between the vertical slides 69, 69' and the design carrier 1, that the connecting gearing serves to lock the carrier and the two vertical slides from relative movement so that the two will move in unison upon the vertical guides 3 when any external force is applied thereto.

It will be noted from the foregoing description that if the bar clamp nut 63 is released so as to free the vertical slides 69, 69' so that they may be moved on the vertical guides 3, if then the hand wheel 73 is rotated and the design carrier 1 either locked by some suitable clamp or kept in its position due to the inertia of its mass, the rotation of the screws 77, 77' will cause the vertical slides 69, 69' to move vertically on the guides 3 with respect to the design frame and along the scale thereon.

Since the angle of the bar 55 is increased as the slide 69 is elevated, it follows that the extent of downward movement of the slide 69 and design carriage when locked together and driven by the differential apparatus, will be proportional to the extent of vertical adjustment of the slide 69 from the bottom of the scale. If, therefore, some indicating mark 82 is placed on the vertical slide 69 cooperating with the scale so as to indicate upon the scale the vertical distance of slide block pin 67 from the line of travel of pin 56 for any position of slide 69, the scale and indicating means will provide a ready means of determining the proper adjustment or setting of the vertical slide 69 and the inclined bar 55 for any desired travel of the carriage. The indicating means on slide 69 is here shown in the form of a vernier for fine readings.

Immediately in front of the design carrier 1 is mounted suitable apparatus for providing the long narrow horizontal light slot 80. This apparatus (Fig. 8) consists of two horizontal flanged bars 83, 83' having at each end end bosses 84, 84' slidable in grooves 85, 85' carried at the upper end of uprights 86, 86' mounted on a cross bar 87 of the main frame. The bars 83, 83' are ad-

justable toward and from each other by means of screws 88, 88' operated by bevel gearing 89, 89' from horizontal shaft 90 operated by hand wheel 91. The edges of this slot, as shown in Fig. 8, terminate in close proximity to the adjacent surface of the design plate, and the height of the slot is adjusted to give the desired height to the long narrow image-carrying beam of light to be projected by the lens onto the sensitized surface. At the other end of the machine corresponding apparatus is provided (see Figs. 1, 9, 10 and 11) for providing a light slot at the focal plane of the lens tangent to the sensitized roller. This is shown in the form of two horizontal bars 92, 92' mounted on brackets slidable on two upright columns 93, 93' and adjusted theron by means of screws 94, 94' so as to vary the height of the light slot according to the requirements of the work to be performed. If a beam of light of too great a height be allowed to strike the cylindrical surface of the sensitized roller, there will be a certain amount of distortion of the image as projected upon the cylindrical surface, and hence the necessity for the light openings.

When the roller is being trued up with respect to the focal plane of the lens, the position-determining means 31, 31' for this purpose, heretofore mentioned, are mounted slidably upon a horizontal bar 95 which is temporarily secured to the uprights 93, 93' by curved ends of the bar which fit around reduced sections 96, 96' of the uprights 93, 93' to which the bar is clamped by hand-operated adjustment bolts 97, 97' operating in threaded holes in the uprights. Further means of adjustment of the bar with respect to the uprights is provided for by the small screws 98 (Fig. 11) threaded in the curved end of the bar and bearing upon the upright. By this mechanism the bar 95 may be slightly adjusted back and forth in a horizontal plane.

In order to examine the focus of the projected image in the focal plane of the lens along the entire width of the sensitized roller, a small slide 99 is provided adapted to fit upon the horizontal guide bar 95 in the same manner as the slide 31 fits upon it, and this slide 99 is adapted to have clamped thereto in any suitable manner, a small focusing ground glass 100 adapted to lie in the intended focal plane of the lens tangent to the sensitized roller, and to be slid along the bar 95 so as to examine the design image throughout its desired width along the axis of the roller before commencing the projection of the same onto the roller. When the proper focus has been obtained, this slideable ground glass is removed and then the roller position-determining means 31 may be put in place on the bar 95 for adjustment of the roller to the focal plane of the lens, where-

upon the bar 95 may be removed and the bars 92, 92' adjusted for the desired height of the light slot prior to projection.

The method of adjusting and operating the machine described may be as follows: Say we are using in the machine a lens adapted and positioned to project an image of the design onto the focal plane, 3 times the size of the original design, i. e., with the ratio of projection 3 to 1, and we desire to place this design on a roller the circumference of which is 21 inches, and that the desired width of the design along the roller for printing purposes is to be 36 inches. In such case we would provide a design plate 7 inches high and 12 inches wide. This plate will be properly centered longitudinally of the design carrier 1 by any suitable device, and adjusted so that the base or lower extremity of the design lies in horizontal alignment with the starting point of the scale 81, such for example, as in alignment with the division 5 shown in Fig. 5. With the bar clamping nut 62 now tightly clamped to hold the bar and the vertical slide 69 from movement, the hand wheel 73 on the design carrier is rotated to bring the scale division 5, and hence the base of the design, in alignment with the central horizontal plane of the light slot 80, whereupon the clamping nut 62 is released; and then with the carriage 1 either locked in position from vertical movement or held stationary by its inertia, the hand wheel 73 is again rotated to move the relatively light vertical slide 69 upward along the guides 3 until the mark on the vernier comes opposite the division 7 on the scale, at which position the slide bar 55 will have the proper angle to produce 7 inches of movement of the carrier 1 and hence of the design plate. At this position the nut 62 is again turned to lock the slide 69 and bar 55 firmly in position from further vertical movement. This being done, the slide 69 and carriage 1 are now locked together from relative vertical movement, through the screws 77, 77', and this end of the apparatus is now ready to be operated by the differential apparatus. The light slot 80 having been suitably adjusted, the lens is next properly positioned on its short longitudinal slideway to give the desired ratio of projection of the image. The size of this projected image may be measured in any desired well known manner, to see if it will be of the desired proportions, i. e., 21 inches high by 36 inches long the axis of the roller. If this is found to be the case, then the ground glass slide may be put in position on the horizontal bar 95 and slid along the bar to examine the focus of the image throughout the width of the image. If this is found to be satisfactory the roller position-determining means 31, 31', are next slipped into position, and after the light is

shielded or put out, the design roller through mechanism already described, is adjusted up to its position tangent to the focal plane, whereupon the apparatus is ready to have the control lever 10 thrown to start the simultaneous linear movement of the design carrier and rotary movement of the roller, in the manner heretofore described; the rotation of the roller being arrested at the end of one complete revolution, also as heretofore described.

It will be understood that changes and modifications may be made in the form and arrangement of the differential apparatus for causing the design plate to be moved at a rate of speed constant to the peripheral velocity of the roller. For example, in the particular differential apparatus here shown the arrangement may be such that the functions of the slide block 64 and the inclined bar 55 may be just reversed. In this case the slide block 64 could be connected to the horizontally movable carriage 47 to move back and forth along the horizontal path now traveled by the pivot pin 56, and the inclined bar 55 could be secured to the vertically movable slide 69 and be provided with suitable vertical guides to cause it to move vertically with the said slide 69 so that the travel of the guide block 64 operating on the bar 55 will move the design carriage.

It is sometimes the case that for use with the desired ratio of projection the design plate has not been made to dimensions that bear the desired ratio to the circumference of the roller or to the length of the roller. Say for example, with a ratio of projection of 3 to 1 and with the circumference of the sensitized roller 21 inches and the desired length of the roller 36 inches, it is found that the design plate or negative instead of being 7 inches high and 12 inches wide, is 7 inches high and 11 inches wide. The discrepancy in the width of the image along the roller can be taken care of by a slight adjustment of the lens so as to increase the ratio of projection to enlarge the image along the length of the roller, but obviously if the ratio of the velocity of the roller to the rate of travel of the design carrier was made equal to this increased ratio of projection, as would be normally the case, it would cause the image of the design to overlap around the periphery of the roller since the ratio of the height of the design to the periphery of the roller was of the correct predetermined 3 to 1 ratio; and hence to take care of this trouble it is necessary that the ratio of the peripheral velocity of the sensitized roller to the rate of travel of the design carrier must not remain equal to the new ratio of projection to be used in transferring the design, but must be made equal to the original ratio of the circumference of the roller to the height of the design.

(i. e., 3 to 1). This is readily accomplished by merely adjusting the vertical slide 69 to the reading 7 on the scale 80. This means that the design carriage will be given a somewhat faster rate of travel downwardly past the light opening, than it would have had if the ratio of its rate of travel to the peripheral velocity of the roller had been made inversely proportional to the actual ratio of projection used. As a result of this relatively fast rate of travel of the design plate the image of the design will be somewhat foreshortened throughout its entire length around the rollers from what it would otherwise have been. But since this is a uniform condition throughout the length of the design around the roller, and since the difference is distributed throughout the periphery of the roller, it will be unnoticeable and negligible. The situation, of course, is equally well taken care of where the width of the design bears the correct ratio to the length of the roller, but where there is an error in the height of the design on the plate as compared to the circumference of the roller.

Fig. 13 merely illustrates a modification of the apparatus shown in the other figures, wherein the main elements, i. e., the rotary support for the sensitized roller, the lens and the frame for the design carriage, are each mounted on carriages capable of sliding in guides longitudinally of the main frame, so as to adapt the apparatus for use in connection with automatic focusing means which link up these elements and cause them to slide one with respect to another along the main carriage to maintain automatic focus, as is well understood in the art, or so as to enable them to be used with various lenses and manually focused. In this modification the vertical uprights 3" for the design carriage are mounted on a horizontally sliding carriage 3^a and the horizontally slidable differential carriage 47" is adapted to slide back and forth along the carriage 3^a, and since the position of carriage 3^a along the main bed of the machine will be shifted from time to time with respect to the position of the sensitized roller, it will be necessary in this modification to provide some suitable coupling between the differential carriage 47" and its longitudinally operating rod, to permit proper adjustment of the carrier with respect to the longitudinal operating rod such as the rod 43 in Fig. 4. The lens 13" in this form is simply mounted on a carriage with a longer longitudinally throw or movement, and at the other end of the machine the roller support 5" with its adjusting and rotating mechanism, are all mounted on a longitudinally sliding carriage 101.

While we have described our invention in detail in connection with the present pre-

ferred embodiment of the same, it will be obvious to those skilled in the art, after understanding the invention, that various modifications in the arrangement, construction and combinations of parts may be made without departing from the spirit or scope of the invention, and we aim in the appended claims to cover all such changes and modifications as are within the scope of the invention.

Having thus described our invention, what we claim as new and desire to secure by Letters Patent, is:—

1. In apparatus of the character described, the combination of a vertically movable carrier for a design, a rotatable support for a roller with a sensitized surface, means for moving the carrier and rotating the support so as to cause vertical movement of the carrier in unison with rotary movement of the sensitized roller, said means comprising an adjustable differential apparatus for regulating the rate of movement of the carrier with respect to the peripheral velocity of the sensitized surface and having a member connected with the roller to move a fixed distance for one rotation of the roller and having co-operating means connected with the carrier to be moved a variable extent for one rotation of the roller depending upon the adjustment of the differential apparatus, said co-operating means including a sliding part slidably mounted upon a vertical guide to move parallel with the design carrier and a screw shaft connecting said sliding part with the design carrier to thereby adjust the sliding part with respect to the carrier when the screw shaft is rotated, and to move the carrier with the sliding part when the latter is actuated by the aforesaid member connected with the roller, indicating means on said slidable part and a co-operating scale operatively related to said indicating means for indicating the distance through which the carrier is to be moved by the sliding part, and for determining by the setting of said indicating means with respect to said scale the setting of the adjustable differential apparatus for producing proper movement of the carrier.

2. In apparatus of the character described, the combination of a linearly movable carrier for a design, a rotatable support for a roller with a sensitized surface, and means for moving the carrier and rotating the support so as to cause linear movement of the carrier in unison with rotary movement of the sensitized roller, the carrier-operating means comprising two co-operating members, one a slide block and the other a slideway, one of said members being moved linearly as distinguished from rotatably and in unison with the rotation of the rotatable support, the other member being

connected with the design carrier to move the carrier in unison therewith, said members being so related that the movement of the actuating one of the members produces a rate of movement of the other which is constant relative to the peripheral velocity of the sensitized roller.

3. In apparatus of the character described, the combination of a linearly movable carrier for a design, a rotatable support for a roller with a sensitized surface, means for moving the carrier and rotating the support so as to cause linear movement of the carrier in unison with rotary movement of the sensitized roller, the carrier-operating means comprising two co-operating members, one a slide block and the other an inclined slideway, one of said members being moved linearly as distinguished from 20 rotatably and in unison with the rotation of the rotatable support, the other member being connected with the design carrier to move the carrier in unison therewith, said members being so related that the movement 25 of the actuating one of the members produces a rate of movement of the other which is constant relative to the peripheral velocity of the sensitized roller, means for adjusting the inclination of the slide with 30 respect to its path of movement to determine the travel of the carrier, and means for projecting the design onto the sensitized surface.

4. In apparatus of the character described, the combination of a linearly movable carrier for a design, a rotatable support for a roller with a sensitized surface, means for moving the carrier and rotating the support so as to cause linear movement of the carrier in unison with rotary movement of the sensitized surface, the carrier-operating means comprising a slide block and a co-operating linearly movable slide inclined to its path of movement relative to the block 45 to actuate the latter when moved, said slide being connected with the rotatable support to be moved simultaneously therewith and at a rate of speed constant with respect to the peripheral velocity of the sensitized roller, the slide block being connected with the design carrier to actuate the latter at a rate of speed constant with respect to that of the block, and means for projecting the design onto the sensitized surface.

5. In apparatus of the character described, the combination of a linearly movable carrier for a design, a rotatable support for a roller with a sensitized surface, means for moving the carrier and rotating the support so as to cause linear movement of the carrier in unison with rotary movement of the sensitized surface, the carrier-operating means comprising a slide block and a co-operating linearly movable slide inclined to its path of movement relative to the block

to actuate the latter when moved, said slide being connected with the rotatable support to be moved simultaneously therewith and at a rate of speed constant with respect to the peripheral velocity of the sensitized roller, the slide block being connected with the design carrier to actuate the latter at a rate of speed constant with respect to that of the block, means for adjusting the inclination of the slide with respect to its path of movement to determine the travel of the carrier, and means for projecting the design onto the sensitized surface.

6. In apparatus of the character described, the combination of a linearly movable carrier for a design, a rotatable support for a roller with a sensitized surface, means for moving the carrier and rotating the support so as to cause linear movement of the carrier in unison with rotary movement of the sensitized surface, the carrier-operating means comprising a slide block and a co-operating linearly movable slide inclined to its path of movement relative to the block to actuate the latter when moved, said slide being connected with the rotatable support to be moved simultaneously therewith a predetermined distance for one revolution of the rotatable support and at a rate of speed constant with respect to the peripheral velocity of the sensitized roller, the slide block being connected with the design carrier to move therewith transversely of the slide when the latter is shifted, whereby the carrier is caused to move a predetermined distance for one rotation of the sensitized roller and at a rate of speed constant with respect to the peripheral velocity of said roller, and means for projecting the design onto the sensitized surface.

7. In apparatus of the character described, the combination of a vertically movable carrier for a design, a rotatable support for a roller with a sensitized surface, means for moving the carrier and rotatable support so as to cause linear movement of the carrier in unison with rotary movement of the sensitized surface, the carrier-operating means comprising a slide block connected to the carrier to move vertically therewith, a carriage connected with the rotatable support and adapted to be moved simultaneously therewith horizontally and transversely to the path of movement of the design carrier, said horizontally movable carriage being adapted to move a predetermined distance for one rotation of the sensitized roller, and inclined slide swiveled on said horizontally movable carriage and means for adjusting the angle of inclination of the slide with respect to the path of movement of said last carriage, and a slide block connected to the vertically movable design carrier to move therewith and operatively engaging the inclined slide, so as to cause the carrier to move

vertically when the horizontally movable carriage is shifted.

8. In apparatus of the character described, the combination of a linearly movable carrier for a design, a rotatable support for a roller with a sensitized surface, means for moving the carrier and rotating the support so as to cause linear movement of the carrier in unison with the rotary movement of the sensitized roller, means for projecting the design onto the sensitized surface of the roller, including a lens between the design and the roller, two adjacent relatively adjustable members in front of the design providing between them a long narrow light-transmitting slot extending along the design transparency closely adjacent thereto, means at each end of said members for supporting and adjusting same to regulate the height of the slot, means in front of and adjacent the surface of the sensitized roller for providing a long narrow light slot closely adjacent the surface of the roller and extending substantially parallel therewith, said last means also comprising two relatively adjustable members with means for adjusting the same to vary the height of said light slot.

9. In apparatus of the character described, the combination of a linearly movable carrier for a design, a rotatable support for a roller with a sensitized surface, means for moving the carrier and rotating the support so as to cause linear movement of the carrier in unison with rotary movement of the sensitized roller, means for projecting the design onto the sensitized surface, and adjustment means for positively and simultaneously arresting the travel of the carrier and the rotation of the roller at the end of one complete rotation of the roller, said stop means comprising a rotatable member geared with the rotatable support and carrier, and a co-operating stop for arresting the rotation of said rotatable member at the end of less than one complete revolution of said member.

10. In apparatus of the character described, the combination of a vertically movable carrier for a design, a rotatable support for a roller with a sensitized surface, means for moving the carrier and rotating the support so as to cause vertical movement of the carrier in unison with rotary movement of the sensitized roller, said means comprising an adjustable differential apparatus for regulating the rate of movement of the carrier with respect to the peripheral velocity of the sensitized surface and having a member connected with the roller to move a fixed distance for one rotation of the roller and having a co-operating member connected with the carrier and movable a variable extent for one rotation of the roller depending upon the adjustment of the differential apparatus, the carrier-

moving means also comprising a slide adjacent the design carriage and slidably mounted upon a vertical guide to move parallel with the design carrier and connected to the variable movement member of the differential apparatus to be moved thereby and gearing connecting said slide with the design carrier to move one with respect to the other and capable, when not being operated, to lock said carrier and sliding member together from relative movement, indicating means on said slide member and a scale on the carrier operatively related to said indicating means for indicating the distance through which the carrier is to be moved and determining by the setting of said indicating means with respect thereto the setting of the adjustable differential apparatus for producing the proper movement of the carrier.

11. In apparatus of the character described, the combination of a linearly movable carrier for a design, a rotatable support for a roller with a sensitized surface, means for moving the carrier and rotating the support so as to cause linear movement of the carrier in unison with rotary movement of the sensitized roller, means for projecting the design onto the sensitized surface of the roller, position-determining means in front of the roller comprising a part at each end of the roller to co-operate with each end of the roller, said means lying substantially in the focal plane of the lens where it is desired to position the periphery of the roller, and means for adjusting each end of the rotary support of the roller toward and from said means so as to true up the roller with respect to said focal plane.

12. In apparatus of the character described, the combination of a linearly movable carrier for a design, a rotatable support for a roller with a sensitized surface, means for moving the carrier and rotating the support so as to cause linear movement of the carrier in unison with rotary movement of the sensitized roller, means for projecting the design onto the sensitized surface of the roller, a focusing ground glass and means for slidably mounting same so that it will lie substantially in the focal plane and travel along a line defined by the intersection of said focal plane with the horizontal axial plane of the roller, whereby by sliding the ground glass along said line the focus of the design throughout its entire width may be examined in the focal plane at the position where the image of the design is to be progressively projected onto the roller.

In testimony whereof we have signed our names to this specification.

JOHN DARBY.
HARRY C. JONES.
